UNITED STATES PATENT OFFICE.

PAUL M. HENGSTENBERG, OF WILKINSBURG, PENNSYLVANIA, ASSIGNOR TO WESTINGHOUSE ELECTRIC & MANUFACTURING COMPANY, A CORPORATION OF PENNSYLVANIA.

SHORT-CIRCUITING DEVICE.

Application filed July 27, 1922. Serial No. 577,840.

My invention relates to short-circuiting devices and it has particular relation to centrifugally operated mechanism adapted to be employed with dynamo-electric machines to effect a repulsion operation during the starting period and induction operation during the normal operating period thereof.

One of the objects of my invention is to provide a short-circuiting device, of the character described, which provides a very simple and inexpensive method of mounting and adjusting the tension of the several spring members that tend to maintain the short-circuiting element out of contact with the commutator segments of the machine.

Another object of my invention is to provide a device, of the character described, which includes a short-circuiting element of unitary structure that may be constructed from a single sheet metal blank with comparatively few operations.

A still further object of my invention is to provide a device, of the character set forth, which is simple in construction and operation, comprising relatively few parts which may be quickly and easily assembled and adjusted with a minimum of time and expense.

In the accompanying drawing,

Fig. 1 is a side elevational view of a dynamo-electric machine, a portion of which is broken away to illustrate a short-circuiting device constructed in accordance with my invention;

Fig. 2 is an end elevational view, on a larger scale, of the device illustrated in Fig. 1, a portion of the short-circuiting element being broken away to better illustrate the supporting member therefor; and

Fig. 3 is a side elevational view of the short-circuiting device illustrated in Fig. 2.

Referring to the drawings, a dynamo-electric machine, embodying my invention, is illustrated as comprising a stator member 1 that is provided with end bells 2. A rotor shaft 3 is journaled in bearings 4 that are provided on the end bells 2 and carries a commutator cylinder 5.

A short-circuiting device, indicated as a whole at 6, (Fig. 1) is mounted on the rotor shaft 3 adjacent to the outer end of the commutator cylinder 5. The short-circuiting device 6 preferably comprises a supporting member 7, which consists of a hub portion 8 and a substantially conical or inclined annular wall portion 9, and which is adapted

to be secured to the rotor shaft 3 by means of a set screw 10 that is located in the hub portion 8. The hub portion 8 is provided with a sleeve 11 which extends inwardly toward the commutator cylinder 5.

The supporting member 7 is preferably constructed of cast metal and is provided with a plurality of equally spaced radially extending webs or flanges 12 which are formed integrally with the hub portion 8 and with the wall portion 9 and serve to reinforce and strengthen the structure.

A short-circuiting element 13 is slidably mounted upon the sleeve 11, for movement in an axial direction, and is secured to the supporting member 7 by means of a plurality of equally spaced coiled springs 14. The outer ends of the springs 14, that is to say, the extremities thereof which are furthest removed from the commutator cylinder 5, project through apertures 15 that are provided in the wall portion 9 of the supporting member 7, and are secured to the web portions 12 thereof, as at 16. The web portions 12 are preferably cut away, as indicated at 17, to permit the spring members 14 to extend through the apertures 15.

The inner extremities of the springs 14 project through apertures that are provided in the short-circuiting element 13 and are secured to the latter by means of nuts 18. The nuts 18 comprise metal disks, each of which is provided with a central aperture 19 through which the springs 14 are adapted to project. The diameter of the apertures 19 is slightly less than that of the springs 14 and, as a consequence, the relatively thin disks extend inwardly between the convolutions of the springs and permit of a screw thread action thereof. The disks or nuts 18 may be rotated to adjust or regulate the tension of the springs 14 by means of lip portions 20, which are struck up from the body portion of the disks 18.

The short-circuiting element 13 is preferably constructed from a single sheet metal blank that is provided with a curled edge portion 21. This edge portion is adapted to be moved into engagement with the extremities of the segments of the commutator cylinder 5, as will be hereinafter described. The curled edge portion 21 of the short-circuiting element 13 is provided with a plurality of radially extending slots 22, which divide the commutator-engaging portion of

the short-circuiting element 13 into a plurality of resilient contact fingers 23.

By this construction, the yieldability of the contact portion of the short-circuiting element 13 is materially increased and an efficient electrical contact with the commutator cylinder is insured, notwithstanding any slight irregularities that may exist in the contact surface thereof by reason of differences in the lengths of the commutator segments. Moreover, the range of resilient movement of the several contact fingers 23 is sufficient to effect a combined rocking and sliding action of the fingers when the short-circuiting element is forced into engagement with the end of the commutator cylinder. This action tends to remove any dust, oil or other foreign matter that may have collected upon the contact surfaces of either the cylinder or the fingers.

A plate 24 is secured to the outer face of the short-circuiting element 13 and provides a bearing surface for a plurality of relatively heavy balls 25, which are loosely mounted between the inner surface of the wall portion 9 of the supporting member 7 and the outer surface of the plate 24. The balls 25 are maintained in equally spaced relation with respect to each other by means of a plurality of spaced and parallel guide members or flanges 26 that are preferably cast integrally with the wall 9.

When the machine is not in operation or when it is operating at a very low starting speed, the springs 14 maintain the short-circuiting element 13 out of contact with the commutator cylinder 5, but as soon as the machine attains a predetermined peripheral speed by reason of its operation as a repulsion motor, centrifugal force will cause the balls 25 to move radially outwardly between the guide members 26. The inclination of the wall 9 is such that as the balls 25 move outwardly they will wedge between the wall 9 and the short-circuiting element 13, thus forcing the latter axially into short-circuiting engagement with the extremities of the segments of the commutator cylinder 5 to

effect an induction operation of the machine during the normal operating period thereof.

By means of the previously described construction, a very efficient short-circuiting device is provided that not only comprises relatively few parts which may be easily assembled, but in which practically all of the various elements may be constructed either from cast metal or from pressed sheet metal blanks, thereby effecting a material reduction in manufacturing expense.

I claim as my invention:

1. A short-circuiting device for a commutator-type dynamo-electric machine comprising a supporting member consisting of a hub portion and a substantially conical wall portion provided with a plurality of equally spaced apertures, web members disposed adjacent to said apertures and connecting said wall portion and said hub portion, and an axially movable short-circuiting element disposed adjacent to said wall portion and connected thereto by means of a plurality of springs that are adapted to extend through said apertures and be secured to said web portions.

2. A self-contained contact making and breaking device adapted to be mounted on the shaft of a rotating electrical device, comprising a supporting member having a tubular member adapted to be secured to said shaft and a substantially conical wall portion mounted on one end of said tubular member, an axially movable contact member mounted on the other end of said tubular member, a plurality of rolling centrifugal weights disposed between said conical member and said contact member, means for restraining said weights to movement in substantially radial planes passing substantially through the center line of said shaft, and a plurality of tension springs disposed between said radial planes for drawing said contact member toward said conical member.

In testimony whereof, I have hereunto subscribed my name this 15th day of July, 1922.

PAUL M. HENGSTENBERG.
